UNITED STATES PATENT OFFICE.

CHARLES GREEN, OF GREENVILLE, DELAWARE, ASSIGNOR OF ONE-HALF
TO WILLIAM WILSON, JR., OF SAME PLACE.

SHEET-METAL CAN.

SPECIFICATION forming part of Letters Patent No. 245,371, dated August 9, 1881.

Application filed June 11, 1881. (No model.)

To all whom it may concern:

Be it known that I, CHARLES GREEN, of Greenville, Delaware, have invented an Improvement in Sheet-Metal Cans, of which the following is a specification.

5 My invention relates, generally, to the class of sheet-metal vessels employed to hermetically contain liquid paints, preserved edibles, powder, and kindred substances, and which are known in the trade as "wire-rippling cans," while it relates specifically to a can invented by me, and forming the subject-matter of an application executed and filed by me contemporaneously with this application.

10 15 In my invention above referred to a wire is adapted to rupture an envelope of solder, which alone secures together the parts which are to be separated to open the can.

The object of my present improvement is to 20 provide means whereby the wire is with greater readiness retained in place during the process of securing the cover or sealing the can, and whereby strains upon the solder-envelope are lessened.

25 25 To the above ends my invention consists in the improvement hereinafter described and claimed.

In the accompanying drawings, Figure 1 is a view, in perspective, of the cover of the can. 30 Fig. 2 is a similar view of a band of sheet-iron or other material to which solder will not adhere, employed in my former invention to prevent improper adherence of the solder. Fig. 3 is a similar view of the ripping-wire. Fig. 4 is 35 a central sectional elevation of the upper portion of the can embodying my present improvement, with the cover represented as sealed in place; and Fig. 5 is a view, in perspective, of a closed and sealed can embodying my invention.

40 Similar letters of reference indicate corresponding parts.

In the accompanying drawings, A represents a flanged cover, and B a band of sheet-iron or other material to which solder will not adhere, placed between the flange of the cover and the chine of the can.

45 C is the body of the can, D the ripping-wire, and E the envelope of solder. These

parts, in a given relative arrangement, constitute the features of my former invention.

G is a circumferential corrugation formed in the upper portion of the can-body below the chine. It opens outward, and is of such depth and extent as to afford a means for locating 55 and partially retaining the ripping-wire in the operation of sealing the can. In the provision of this circumferential groove, in combination with the members forming the elements of my former invention, this improvement consists. 60

In the sealing of a can constructed according to this improvement, after the cover has been placed in position, the wire is laid in the groove, in which position the wire resting in the groove comes in contact with the lower 65 edge of the sheet-iron band only, or with the lower edge of both band and flange of the cover, and an envelope of solder extending from the lower edge of the flange to the body below the groove is then applied to secure the 70 wire in place.

The advantage of my improvement is that it assists in locating and retaining the wire during the sealing operation, and also serves to relieve strains upon the solder-envelope, 75 which heretofore alone retained the wire.

Having thus described my invention, I claim and desire to secure by Letters Patent of the United States—

In a sheet-metal can, the combination of a 80 flanged cover, a body provided with a circumferential groove adapted to form a seat for a ripping-wire, a band or ring of sheet-iron, or other material to which solder will not adhere, between the flange of the cover and the body 85 above the groove, a ripping-wire seated in said groove, and a solder-envelope inclosing the wire and uniting the flange of the cover with the body of the can below the wire and the groove, substantially as and for the purposes set forth.

In testimony whereof I have hereunto signed my name this 26th day of May, A. D. 1881.

CHARLES GREEN.

In presence of—

J. BONSALL TAYLOR,
W. C. STRAWBRIDGE.
